CLAIM

The ornamental design for a remote control holder, as shown and described.

DESCRIPTION

FIG. 1 is a perspective view from above of a remote control holder in accordance with my design;

FIG. 2 is a side elevation view of the remote control holder in accordance with my design, the opposite side being a mirror image of that shown;

FIG. 3 is a front plan view of the remote control holder in accordance with my design;

FIG. 4 is a back plan view of the remote control holder in accordance with my design, the opposite side being a mirror image of that shown;

FIG. 5 is a top elevation view of the remote control holder in accordance with my design; and,

FIG. 6 is a bottom elevation view of the remote control holder in accordance with my design.
